UNITED STATES PATENT OFFICE.

THOMAS C. SHEEHAN, OF UPPER MONTCLAIR, NEW JERSEY, ASSIGNOR TO DURHAM
DUPLEX RAZOR COMPANY, OF NEW YORK, N. Y., A CORPORATION OF NEW YORK.

RAZOR-BLADE.

1,266,368.

Specification of Letters Patent. Patented May 21, 1918.

Application filed October 4, 1917. Serial No. 194,761.

To all whom it may concern:

Be it known that I, THOMAS C. SHEEHAN, a citizen of the United States, residing at Upper Montclair, county of Essex, and State of New Jersey, have invented a new and useful Improvement in Razor-Blades, of which the following is a specification.

This invention relates to an improvement in razor blades, particularly of the type used in safety razors. The invention consists in certain constructions which will be hereinafter fully described and then specifically pointed out in the claims hereunto appended.

In the accompanying drawings, which form a part of this specification and in which like characters of reference indicate the same or like parts, Figure 1 is a plan view of a blade constructed in accordance with the invention; Fig. 2 is an end view of the structure shown in Fig. 1; Fig. 3 is a plan view of a modification of the structure shown in Fig. 1, adapted for use in a different type of blade holder; and Fig. 4 is a modified form of the structure shown in Fig. 1.

In carrying the invention into effect, there is provided a razor blade comprising two sections each having a cutting outer edge and an inner edge interlocked with the inner edge of the other section, the principal advantage of this construction lying in the possibility of substituting a perfect half blade for one that has been accidentally injured, without discarding a whole blade. In the best constructions, each of the sections has a hard outer cutting edge and a soft inner edge, and the junction line of the two sections is substantially on the median line of the blade.

Referring to Fig. 1 of the drawings, 6 and 7 indicate two like blade sections, the section 6 having a hard cutting edge 8, and the section 7 having a hard cutting edge 9. The blade as a whole is provided with an elongated slot 10, used for the purpose of positioning it on a suitable blade holder. The parting line of the two blade sections 6 and 7 is substantially on the median line of the blade, as clearly shown in Fig. 1. The section 6 has a dovetailed lug 11 closely fitting a dovetailed slot 12 in the section marked 7. Similarly, the blade section 7 has a dovetailed lug 13 snugly fitting a dovetailed slot 14 in the blade section 6.

The temper is drawn from the lugs 11 and 13, so that they are soft and easily fitted respectively to the slots 12 and 14. By an inspection of Figs. 1 and 2, it will be readily understood that the interlocking of the two blade sections is effected by a transverse relative movement of the two sections, and that therefore they are transversely interlocked, and when in interlocked position they lie in the same plane.

In the modification shown in Fig. 3, the two blade sections 15 and 16 are respectively provided with dovetailed lugs 17 and 18, similar in all respects to those in the device shown in Figs. 1 and 2. In place of the elongated holding slot shown in Fig. 1, the device of Fig. 3 has three round holes 19 by means of which it is positioned on a suitable holder.

In the modification illustrated in Fig. 4, the blade sections 20 and 21 are respectively provided with lugs 22 and 23, and with lugs 24 and 25 arranged to interlock, as clearly shown.

When the interlocking lugs are soft, a blade of either type shown may be used either in a holder having a flat supporting member for the blade and a flat holding member, or in a holder provided with curved supporting and holding members. In the latter case, the blade may be given a permanent set as bent by the clamping action of the supporting and holding member.

Changes and variations may be made in the structure by means of which the invention is carried into effect. The invention therefore is not to be restricted to the precise details of the structure shown and described.

What is claimed is:

1. A razor blade comprising two sections each having a cutting outer edge and an inner edge and each provided with an undercut projection snugly fitting a corresponding recess in the inner edge of the other section.

2. A razor blade comprising two sections each having a hard cutting outer edge and a soft inner edge and each provided with an undercut projection snugly fitting a corresponding recess in the inner edge of the other section.

3. A razor blade comprising two sections each having a cutting outer edge and an

inner edge and each provided with an undercut projection snugly fitting a corresponding recess in the inner edge of the other section substantially on the median line of the blade.

4. A razor blade comprising two sections each having a cutting outer edge and an inner edge and each provided with a dovetailed projection snugly fitting a corresponding recess in the inner edge of the other section.

5. A razor blade comprising two sections each having a cutting outer edge and an in-

ner edge and each provided with an undercut projection transversely engaging a corresponding recess in the inner edge of the other section. 15

6. A razor blade comprising two sections lying in the same planes and each having a cutting outer edge and an inner edge and each provided with an undercut projection snugly fitting a corresponding recess in the inner edge of the other section. 20

In testimony whereof, I have signed my name to this specification.

THOMAS C. SHEEHAN.
